UNITED STATES PATENT OFFICE.

JOSEPH EVANS COOPER, OF CRIPPLE CREEK, COLORADO, ASSIGNOR TO COOPER AIRSHIP COMPANY, OF CHICAGO, ILLINOIS.

MILITARY AND PASSENGER AIRSHIP.

1,056,503.

Specification of Letters Patent. Patented Mar. 18, 1913

Application filed September 1, 1911, Serial No. 647,208. Renewed August 26, 1912. Serial No. 717,190

To all whom it may concern:

Be it known that I, JOSEPH E. COOPER, a citizen of the United States, residing at Cripple Creek, in the county of Teller and 5 State of Colorado, have invented certain new and useful Improvements in Military and Passenger Airships; and I do declare the following to be a full, clear, and exact 10 description of the invention, such as will enable others skilled in the art to which it appertains to make and use the same.

This invention relates to aerial navigation, and more especially to dirigible balloons; and the object of the same is to effect 15 certain improvements over my prior patent dated Feb. 14, 1911, and bearing No. 984,076.

To this end the present invention consists in the details of construction hereinafter more fully described and claimed and as 20 shown in the drawings wherein—

Figure 1 is a general side elevation of this air ship; Fig. 2 is a front elevation thereof; Fig. 3 is a section on the line 3—3 of Fig. 1, giving a plan view of the parts supported 25 by the balloon; Fig. 4 is a section on the line 4—4 of Fig. 1; Fig. 5 is a side elevation of the steering devices; Fig. 6 is a cross section through the balloon showing the gas tank therein and the air pouch around the 30 tank; Fig. 7 is another cross section through the balloon showing a different form of its framework structure. Fig. 8 is an enlarged longitudinal section through the rear engine room and the rear portion of the balloon 35 body and one of the gas cylinders, illustrating the connection between the steering mechanism and the rudders and the pipe which feeds gasoline from the tank to one of the engines. Fig. 9 is an enlarged plan 40 view of the rear engine room and rear pilot house and the mechanism therein.

Referring more particularly to the drawings, 1 designates the main gas tank or balloon of this improved air ship, which forms 45 the supporting element and is preferably of aluminum and pointed at its opposite ends as shown, being divided interiorly by partitions 2 into compartments so that if one should leak or burst the others would sustain the machine. The substantially cylindrical body of the tank is maintained in that shape by means of ribs 3 which may be internal as shown in Fig. 6 or external as

shown in Fig. 7, and at suitable points the shell may have safety valves 4 communicating with the various compartments so that an excess of pressure therein will not cause bursting. Disposed preferably along the bottom of the cylindrical body in the central compartment is a gasoline tank 5 from which suitable pipes 53 lead to the engine described below, and in the other compartments are mounted high pressure gas tank 6 each having its own safety valve 7 to prevent bursting in case the pressure should become too high therein. I purposely locate these high pressure tanks within the main tank, because if the former should leak the gas escaping would not escape from the main tank and its buoyant properties would still be employed. Preferably disposed over and lying upon the high pressure tanks are air-pouches 8 made of flexible material such as rubber, each having apertures 9 open to the outside air, and the registering apertures 10 in the cylindrical body of the tank are preferably covered with wire gauze to prevent the pouch itself from being forced out through them by the pressure of gas contained within the tank. These expandable pouches permit air to enter any compartment within the balloon envelop so that the pouch expands automatically sufficiently to take the place of any gas that may be drawn from such compartment or which may escape therefrom, for the combined purpose of preventing the admixture of air with gas and avoiding a tendency of the normal air pressure on the exterior of the casing to collapse it. These pouches have a third and important function, which is to prevent the loss of fluid from the high pressure tanks in case the latter should spring a leak, for the inner wall of each pouch closely surrounds said tank as seen in Fig. 6. And still another function which they possess is that of jacketing such tanks in case the fluid therein is explosive.

An important feature of improvement which I have adopted consists in stringing the collecting wires 12 of a wireless telegraph or telephone outfit beneath the conical front end of the balloon body as shown whereby they are protected to an extent from the elements and yet are exposed as far as possible so as to be susceptible to th-

fluences by means of which communication may be had between this machine and note stations.

Another feature of improvement consists in the location of two engine rooms 13 and 14 at opposite ends of the main gangway 15 which is supported in any suitable manner beneath and preferably extends throughout the length of the cylindrical portion of the body of the tank 1, the cabin and magazine being placed at about the center of the length of said gangway, and the gas pump and dynamos 18 being disposed forward and aft along said gangway and within the engine rooms so that the entire machine will be balanced as nearly as possible. With the same object in view, the four engines with which this machine is provided are disposed two in each engine room and adjacent the sides thereof as indicated at each receiving its supply of gasoline from the tank 5 through a separate tube and each engine being entirely independent of all others so that if one engine should be thrown out of commission it will only impair the propelling mechanism by one-ninth its total. Each engine drives its propellers 20 within a tube 21 having a ring front end 22, and these tubes are disposed at opposite sides of the main gangway and fore and aft as shown. Herein, if any one propeller should be thrown out of commission, the other three would be amply sufficient to drive the machine. The function of the dynamos and gas pump is the same as in my prior patent, and needs no elaboration here.

Another feature of improvement in the present instance relates to the steering apparatus. The vertical rudders 25 are disposed one in rear of each tube 21 so that when there are four and an accident to one to one pair would not disable the control of the air ship. In the present case, however, I have added a horizontal rudder at the rear of the machine, thereby enabling the aviator or pilot to make a rapid ascent or descent without necessarily waiting for the relatively slow operation of pumping gas from one pressure tank 6 or the other. The steering mechanism for all these rudders is best seen in Fig. 5, and herein I have duplicated the mechanism at the front and rear portions of the main gangway 15, and located the pilot houses preferably in the angles 27 at the front ends of the engine rooms 13 and 14. Within each pilot house is erected a standard having a bearing 31 at its upper end through which is journaled a tubular shaft carrying a pulley 32 at one extremity and a hand wheel 33 at the other, and suitable ropes or chains 34 lead from this pulley to a set of rudders. Similarly a smaller shaft is journaled through the tubular shaft

and there is a pulley 35 at one end and a hand wheel 36 at its other end, and from this pulley lead other chains 37 which are connected to the other rudder. Each shaft carries a toothed wheel 38 engaged by a separate latch and treadle mechanism 39 so that after the pulley has been turned by the hand wheel to set the rudder the latch may be engaged with the toothed wheel to lock it in that position. Of course it is possible to connect both steering mechanisms with all the rudders so that two pilots working together may assist each other at times when it is necessary or desirable, or the connection could be broken temporarily so that either pilot could do the steering in his own pilot house irrespective of the other or in the absence of the other. However, as the machine is quite long and the vertical rudders fore and aft are disposed some distance from each other, it may be and preferably is desirable usually to connect up the chains with the pulleys of the steering mechanism in such manner that as the vertical rudders at the front are turned to the right those at the rear are turned to the left so that the machine may be turned about in short compass. This is illustrated theoretically by the dotted positions of the rudders 25 in Fig. 3 and I consider it far more important in a dirigible balloon than in a long land vehicle or long water vehicle. If all the lateral rudders in a balloon were moved in one direction simultaneously the tendency would be to swing the entire gangway to one side and rock the cylindrical tank on its axis, whereas it will be clear that if the fore rudders turn in one direction and the aft rudders in the other this tendency would not obtain. With a vehicle the tendency is overcome by its engagement with the earth or the water.

I purposely refrain from giving sizes, specific structures proportions, or materials of parts because they do not enter into the successful operation of this improved military and passenger air ship. As first stated above, this is an improvement on my former patent in details which have been elaborated above. One other feature of improvement over my prior patent hereinbefore referred to consists in the use of an inclinometer 50, which is a weighted hand pivoted at the point 51, and swinging over a dial 52, and whereof I preferably mount one in each engine room to indicate to the engineer or pilot or both the position of the keel relative to a horizontal line. It is to be understood that these are not the lateral devices ordinarily used on board ships to tell when they are running on even keel, but the pivots 51 stand transverse of the length of my improved air ship so that the pendulums or hands 50 may swing forward and backward as the extremities of the machine rise and fall.

fall; hence it will be seen that it is quite necessary that each engineer and each pilot should know whether the keel stands level or inclined and if inclined in which direction 5 and to what degree.

In Fig. 8 is shown a slight modification, wherein the high pressure gas tank 6 is supported at some little distance above the bottom of the gas tank or balloon 1 by means 10 of brackets 60; and this view also illustrates the gasolene pipe 53 which it will be understood connects at its front end with the tank 5 elsewhere shown and is illustrated herein as leading to the engine 19.

15 What is claimed as new is:

1. In a dirigible balloon, a cylindrical gas-envelop mounted on suitable ribs and divided into compartments by transverse partitions; combined with a liquid fuel tank 20 in the central compartment and high pressure gas tanks in the others, safety valves for the last-named tanks, flexible pouches around certain of the tanks, and independent connections between all said tanks and 25 the machines with which they communicate.

2. In a balloon, the combination with a

cylindrical gas-envelop having safety valves through its wall, tanks within said envelop at the bottom thereof for liquid fuel and for high pressure gas, and safety valves for the last named tank leading through the envelop wall of a flexible pouch within said envelop and resting on said tank but closed to both, and means for throwing its interior into communication with the outside air.

3. In a balloon, the combination with ribs, a rigid gas-envelop carried thereby and a safety valve in the envelop; of a tank within the envelop a flexible air pouch within said envelop around the tank and in free communication through the wall of the envelop with the open air, and wire gauze across the opening in the envelop outside the pouch, for the purpose set forth.

In testimony whereof I have hereunto set my hand in presence of two subscribing witnesses.

JOSEPH EVANS COOPER.
